UNITED STATES PATENT OFFICE.

WELCOME JENCKS, OF MANCHESTER, NEW HAMPSHIRE.

THREAD-GUIDE SUPPORT FOR RING-SPINNING FRAMES.

SPECIFICATION forming part of Letters Patent No. 334,441, dated January 19, 1886.

Application filed June 15, 1885. Serial No. 163,674. (No model.)

To all whom it may concern:

Be it known that I, WELCOME JENCKS, of Manchester, in the county of Hillsborough, of the State of New Hampshire, have invented 5 a new and useful Improvement in the Thread-Guide Supports for Ring-Spinning Frames; and I do hereby declare the same to be described in the following specification, and represented in the accompanying drawings, of

o which—

Figure 1 is a top view of a series of thread-guides provided with my invention, such figure also showing the connecting-shaft of such guides. Fig. 2 is a transverse section taken 15 through one of the guides, such section showing in dotted lines the guide and fore portion of its arm raised into a vertical position. Fig. 3 is a transverse section showing the guide and both portions of its arm as turned 20 upward out of a horizontal position. In Fig. 4 portions F F of the spinning-frame are shown, with the shaft of the guides as applied to them and provided with a handle for turning it.

25 The nature of my invention is defined in the claim as hereinafter presented.

In the said drawings, the yarn-guides are represented at A A, &c., each consisting of a piece of round wire of suitable length, bent 30 near one end spirally, as usual, the guide-shank or longer straight portion *a* of the wire being inserted lengthwise within a cylindrical hole or bore, *b*, made longitudinally in the fore or front portion, *c*, of an arm, *B*. 35 The arm *B* is in two parts, *c* and *d*, jointed or hinged together, so as to enable the front portion, *c*, to be supported in line with the rear portion, *d*, and to be turned upward into a right angle therewith. The rear portion, *d*, of each of the arms *B* is adapted to 40 turn upon a cylindrical shaft or rod, *C*, laterally, and to slide thereon longitudinally thereof, such arm being provided with a set-screw, *e*, for clamping it to the shaft, and such screw 45 being screwed upward into the arm and against the shaft. Furthermore, the shank *a* of each guide A is capable of being slid lengthwise and turned transversely within the fore portion of its supporting arm *B*, a 50 set-screw, *f*, being screwed into the said fore portion and against the said shank. The shaft or rod *C*, arranged horizontally within the

spinning-frame, is supported in bearings *gg* thereof, so as to be capable of being turned transversely, in order to raise all the arms *B*, 55 and their guides simultaneously out of a horizontal into an inclined or a vertical position, F F representing portions of the frame for supporting the operative parts of the machine. The hinge or joint connecting the two 60 portions of each arm *B* is to be such as to support them in a straight line with each other and to enable the front portion to be turned up into an angle with the rear portion. There projects down from the front portion of each 65 arm *B* a hook, *D*, which is to catch a thread or yarn leading through the guide to the traveler when the spindle may be in revolution, and such yarn may have become kinked and broken and thrown out against the hook, 70 such catching of the yarn being to prevent it from becoming entangled or interfering with either of the next adjacent yarns.

From the above it will be seen that the 75 thread-guides are supported by separate arms applied, as described, to a single shaft, and that such arm, is in two parts, jointed together, as explained; also, that each guide can be moved lengthwise and turned transversely in its arm, and besides can be held in place therein by a 80 set-screw; also, that by turning the shaft all the guides and their supporting-arms can be simultaneously raised from a horizontal into a vertical or an inclined position, so as to be out of the way of the bobbins in the process of 85 doffing or removing them from the spindles, or of supplying the spindles with fresh bobbins; also, that each guide can be adjusted nearer to or farther from the shaft or nearer to or farther from the next adjacent guide, as may 90 be necessary to bring the said former guide into its correct position with reference to the spindle immediately below it.

By having the guides applied to arms separated apart from each other or with spaces 95 between them, as represented, most, if not all, of the dust and fibrous matters that usually collect on the thread-guide supports when they are close together and hinged to a rail or bar, as heretofore, will fall through the spaces 100 between the arms, thereby saving the necessity and labor of removing such collections from the supports of the guides. So, by having all the guides provided with means of

raising them simultaneously, the labor of turning the guides in succession upward is saved.

I am aware that the yarn-guides of spinning-
5 frames have been fixed in as many supports hinged to a shelf or rail, so as to be capable of being separately turned upward, each of the said supports being nearly in contact with that or those next it. I therefore do not
10 claim such.

I claim—

The combination, with the frame of a ring-
spinning machine, of a shaft pivoted thereto,

so as to be capable of being turned or re-
volved laterally of it, (the said shaft,) a series 15
of separate arms projecting from and each
adjustable on such shaft lengthwise thereof
and having a set-screw for holding it to the
shaft, and a series of yarn-guide carriers,
hinged to such arms and furnished with yarn- 20
guides applied to them, (the said carriers,) as
set forth.

WELCOME JENCKS.
